GEORGE HENRY WHEARY AND BENJAMIN M. HAMLIN, OF RACINE, WISCONSIN, AS
SIGNORS TO WHEARY TRUNK COMPANY, OF RACINE, WISCONSIN, A CORPORATION
OF WISCONSIN

HAND LUGGAGE

Application filed November 2, 1929. Serial No. 404,297.

This invention relates to certain new and useful improvements in hand luggage, and like that of our copending application, Serial No. 357,088 filed April 22, 1929, is particularly designed to meet the modern travel requirements, of which, light weight is of primary importance.

This invention is also particularly directed to ladies' hand luggage and has as one of its objects to provide greater convenience in packing or placing garments therein and in removing them from the case.

Another object of this invention is to simplify and improve the construction of luggage of the character described.

With the above and other objects in view which will appear as the description proceeds, our invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawings, we have illustrated two complete examples of the physical embodiment of our invention constructed according to the best modes we have so far devised for the practical application of the principles thereof, and in which:

Figure 1 is a perspective view of a hand luggage embodying our invention, said view illustrating the same in open position;

Figure 2 is a fragmentary detail view of the cover illustrating the manner of draping the garments over the garment carrying frame;

Figure 3 is a view similar to Figure 1 illustrating a slightly modified form of our invention;

Figure 4 is a side view of the cover of the modification shown in Figure 3 with a portion thereof broken away and shown in section to illustrate the means for maintaining the garment carrying frame in normal position;

Figure 5 is a fragmentary detail view of said means; and

Figure 6 is an enlarged cross sectional

view taken through Figure 4 on the plane of the line 6-6.

Referring now more particularly to the accompany drawings, the numeral 5 represents the main section of a luggage carrier of the case type having a cover 6 hingedly connected thereto along one marginal edge. The case is further provided with a handle 7 and locking devices comprising main section carried parts 8, and cover carried members 9.

The main section of the case is preferably divided into two compartments 10 and 11 by a partition wall 12 detachably mounted in guideways 13 secured to the opposite side walls 14 of the case. The compartment 11 provides a receptacle for smaller pieces of wearing apparel and its walls which are formed by the section side walls 14, the partition 12, and the front wall 15 of the case, preferably have pockets 16 for the reception of other articles.

The compartment 10, which is considerably narrower than the compartment 11, forms a well into which the ends of garments 17 draped over a garment carrying frame 18 hang. The garment carrying frame is mounted within the cover 6 and consists of side bars 18 hingedly connected at their lower ends to the cover side walls, as at 19, adjacent the hinged connection of the cover with the main section and have their outer ends connected by a bar 20 which is preferably padded to prevent wrinkling of the garments draped thereover.

Being mounted in this manner, the garment carrying frame may be readily swung toward and from a position within the cover, and to limit the outward movement of the frame, the side arms 18 are connected with the cover side walls by pivotally connected link members 21 and 22, the members 21 being secured to the side arms and the members 22 being pivoted to the side walls of the cover.

With the cover 6 in its open position, as illustrated in figures 1, and the garment carrying frame swung outwardly, the bar 20 is disposed substantially over the well formed by the compartment 10, and inas-

much as the cover 6 is held against movement in either direction by a pair of pivotally connected or knuckle jointed links 23 and 24, which, when the cover is in open position, move slightly beyond dead center, the draping of garments over the bar 20 is greatly facilitated.

After the garments have been suitably draped over the garment bar, an elastic strap 25 is connected across the side members 18 outwardly of the garments to hold them in the plane of the frame and against the cover, by engaging hooks 26 carried by its ends in suitable apertures formed in the side members. The garment carrying frame may then be moved inwardly toward the cover to its position illustrated in Figure 2, where it may be secured by a second elastic strap consisting of separated sections 26 and 27. The inner ends of the sections 26 and 27 are secured to the cover and co-operating buckle members 28 and 29 are fixed to their outer ends by which they are connected.

25 To remove all strains from the strap sections 26 and 27 when the case is closed and the garment carrying frame is disposed over the main section, stops 30 are provided upon which the side arms 18 rest.

20 To insure the proper angular movement of the link sections 21 and 22 during movement of the garment carrying frame over the main section, stops 31 are formed on the members 22 to prevent the passage of

35 the point of pivotal connection beyond dead center.

In Figures 3, 4, 5 and 6 we have illustrated a slightly modified form of our invention in which the sectional strap 26 and 27 is dispensed with and a second strap 25 is connected across the outer ends of the frame sides 18.

In this form of our invention the garment carrying frame is readily releasably held in its normal position within the cover by interlocking means carried by the pivotally connected links 21 and 22 and consisting of an aperture 32 formed in each link 22 into which a tip 33, struck from a lateral extension 34 on the links 21, engages when the garment carrying frame is moved to its position within the cover.

With this construction the garment carrying frame need not be separately moved within the cover, for the stops 30 arrest the downward movement of the frame during the closing of the cover and automatically move the frame to its position within the cover.

60 It is noted that like in the aforementioned co-pending application, the bar 20 in both modifications, is directly adjacent the free

edge of the cover when open, so that the removal of one of the innermost garments from the frame is greatly facilitated by throwing back the outer garments over the adjacent free edge of the cover from where they may be conveniently returned to the bar 20 after the desired garment has been removed, without disturbing their arrangement.

From the foregoing description, taken in connection with the accompanying drawings, it will be readily apparent to those skilled in the art to which an invention of the character described appertains, that we provide hand luggage which is greatly simplified in construction and provides maximum convenience during packing and unpacking. 75 80

What we claim as our invention is:

1. Hand luggage of the character described, comprising a main section, a cover hingedly connected thereto, a garment carrying frame including side members having their inner end portions pivotally connected with the cover adjacent its hinged connection with the main section, whereby the garment carrying frame may be swung to and from a position within the cover, pivotally connected link members connecting the garment carrying frame and the cover for limiting outward movement of the garment carrying frame, and means carried by said link members for readily releasably securing the garment carrying frame within the cover.

2. Hand luggage of the character described comprising a main section, a cover hingedly connected thereto, a garment carrying frame including side arms, and a garment supporting member connecting the outer ends of the side arms, means to pivotally connect the inner ends of the side arms with the cover for swinging movement about a fixed axis adjacent the hinged connection of the cover with the main section, said side arms being of such length as to position the garment supporting member near the outer free end of the cover, whereby the garment carrying frame may be swung to and from a position with its garment supporting member within the cover and near the outer free end thereof, means connected to the side arms adjacent their hinged connection with the cover to support the depending portions of garments draped over the supporting member, means connected with a side arm for limiting outward movement of the garment carrying frame with respect to the cover, and means carried by said limiting means for readily releasably maintaining the garment carrying frame within the cover. 100 105 110 115 120 125
